[57] CLAIM

The ornamental design for a bottle portion, as shown and described.

DESCRIPTION

FIG. 1 is a front elevational view of a bottle portion embodying our design wherein the bottle portion is transparent;

FIG. 2 is a front elevational view of a second embodiment thereof;

FIG. 3 is a front elevational view of the embodiment of FIG. 1 wherein said bottle portion is opaque or translucent; FIG. 4 is a front elevational view of the embodiment of FIG. 2 wherein said bottle portion is opaque or translucent;

FIG. 5 is a top plan view of FIG. 3; and,

FIG. 6 is a cross-sectional view of the embodiment of FIG. 4 taken along line 6—6.

The broken lines shown in FIGS. 1 through 5 are for the purpose of showing environmental structure only and form no part of the claimed design.

The rear and side elevations of the four embodiments of the bottle portion are the same in appearance as the front elevations shown in FIGS. 1, 2, 3 and 4.
